FIG. 4

UNITED STATES PATENT OFFICE

2,178,424

ICE SKATE

Charles I. Johnson, Chicago, Ill., assignor to
 Nestor Johnson Mfg. Co., Chicago, Ill., a corporation of Illinois

Application June 7, 1937, Serial No. 146,731

8 Claims. (Cl. 280—11.17)

The present invention relates generally to ice skates. More particularly the invention relates to that type of ice skate which is designed to be permanently attached to a shoe and comprises as the main or essential parts thereof an elongated separately formed runner and a frame which serves to hold the runner in place and support the shoe and consists of a pair of complementary one-piece stamped metal sections each 5 of which is shaped to form (1) an elongated base part having a longitudinally extending inwardly facing groove in its central portion and having the bottom portion thereof, that is, the portion beneath the grooved central portion, laterally deflected to form a seat for the upper portion of the runner; (2) an upstanding web-like front part with the upper portion thereof extending outwardly at right angles and forming a plate-piece for engaging and supporting the 10 sole portion of the shoe; and (3) a web-like rear part projecting upwardly from the rear end of the lower and having the upper portion thereof extending outwardly at right angles to form a plate-piece for engaging and supporting the heel portion of the shoe.

One object of the invention is to provide an ice skate of this type which not only is an improvement upon, and more durable than, previously designed ice skates of the same general 15 character, but also is stronger and lighter and may be produced at a lower cost.

Another object of the invention is to provide an ice skate of the type under consideration in which the runner holding and shoe supporting frame embodies a metallic tube which fits within and 20 extends longitudinally of the grooves in the central portions of the base parts of the frame sections and operates to hold the sections against relative vertical displacement as well as to render 25 them rigid and form an abutment or shoulder for the upper edge of the runner.

Another object of the invention is to provide an ice skate of the aforementioned type and character in which the web-like front and rear 30 parts of the frame sections are shaped to form substantially vertical channels between them and have separately formed metallic tubular struts which fit snugly within the channels and serve to reinforce the web-like front and rear parts 35 against lateral bending or deflection and also to prevent relative longitudinal displacement of the frame sections.

A further object of the invention is to provide a skate of the type hereinbefore referred to in which the plate pieces which are formed by the 40

upper portions of the web-like front and rear parts of the frame sections are deflected to form transversely extending wells thereacross and have cup-shaped members which fit within and extend across the wells and form bridges whereby the 45 plate pieces of one frame section are cross-connected to the plate pieces of the other section.

A still further object of the invention is to provide an ice skate of the type and character hereunder consideration in which the tubular struts in the substantially vertically extending channels between the web-like front and rear parts of the frame sections extend between and engage the cup-shaped members in the wells and the tube between the base-parts of the frame 50 sections and serve to transmit the weight of the person wearing the skate from such cup-shaped members to the tube and thus distribute the user's weight as far as the supporting frame and runner are concerned.

In addition it is contemplated as one of the objects of the invention to provide a skate of the sectional frame type which is generally of new and improved design.

Other objects of the invention and the various 55 advantages and characteristics of the present ice skate will be apparent from a consideration of the following detailed description.

The invention consists in the several novel features which are hereinafter set forth and are 60 more particularly defined by claims at the conclusion hereof.

In the drawings which accompany and form a part of this specification or disclosure and in which like numerals of reference denote corresponding parts throughout the several views:

Figure 1 is a perspective showing a skate embodying the invention with a shoe applied thereto;

Figure 2 is a perspective of the skate without the shoe;

Figure 3 is a plan view of the skate without the cup-shaped members which normally fit within and extend transversely across the wells in the plate-pieces which are formed by the upper 45 portions of the web-like front and rear parts of the frame sections.

Figure 4 is a perspective of one of the frame sections;

Figure 5 is a perspective of the other frame 50 section;

Figure 6 is a perspective of the metallic tube which fits within and extends longitudinally of the grooves in the central portions of the base parts of the frame sections and operates to hold 55

- the sections against relative vertical displacement as well as to render them rigid and form an abutment or shoulder for the upper edge of the runner;
- 5 Figure 7 is a vertical transverse sectional view showing the manner in which the tube fits within the grooves in the central portions of the base parts of the frame sections and forms an abutment for the upper edge of the runner;
- 10 Figure 8 is a vertical transverse sectional view showing the manner in which the metallic tubular struts in the channels between the web-like front and rear parts of the frame sections serve to transmit load or weight from the cup-shaped members in the wells to the tube in the grooves in the base parts of the frame sections;
- 15 Figure 9 is a horizontal section through the web-like front and rear parts of the frame sections;
- 20 Figure 10 is a perspective of one of the cup-shaped members which fit within and extend across the wells and form bridges whereby the plate pieces of one frame section are cross connected to the plate pieces of the other frame section; and
- 25 Figure 11 is a perspective of one of the tubular struts.
- The ice skate which is shown in the drawings constitutes the preferred embodiment of the invention. It is permanently connected, as hereinafter described, to a shoe S and comprises an elongated runner 12 and a frame 13. The runner is formed of steel or any other suitable material. It is narrow and has an ice engaging bottom edge 14 and a frame engaging upper edge 15. The front and rear ends of the runner are curved upwardly so that the extremities thereof will not dig into the ice or otherwise impede the user of the skate during skating. The frame 13 serves, as hereinafter described, to hold the runner 12 in place and is attached to, and serves as a support for, the shoe S. It is of sectional design and consists of a pair of one-piece complementary sections 16 and 17.
- 30 The frame section 16 is in the form of a metal stamping and is shaped to form an elongated base part 18, a web-like front part 19 and a web-like rear part 20. The base part 18 of the frame section 16 is substantially coextensive with the runner 12 and has an inwardly facing longitudinal groove 21 in the central portion thereof. This groove is formed by deflecting the central portion of the base part 18 outwards and extends from a point slightly inwards of the front end 35 of the base part 18 to a point slightly inwards of the rear end of said base part, as shown in Figure 4. It is tapered from the front end thereof to its rear end and is V-shaped in cross-section. The bottom portion of the base part 18 is deflected so that it is laterally offset and forms an elongated seat-forming member 22 for the runner and also an arcuate shoulder 23 at the front end of the member 22 and an arcuate shoulder 24 at the rear end of said member. The seat forming member 22 fits against and is welded to the upper portion of one of the side faces of the runner and the shoulders 23 and 24 are shaped conformably to and bear against the front and rear portions of the upper edge 15 of the runner 40 respectively. The front part 19 projects upwardly from the front portion of the base part 18 of the frame section 16 and its upper portion is bent outwards at right angles to form a plate-piece 25. This piece is shaped to conform to one side of the sole portion of the shoe S and has a series of holes 26 along the margin thereof for rivets or attaching devices (not shown) which serve permanently to connect the shoe to the plate-piece 25. The web-like rear part 20 projects upwardly from the rear portion of the base part 18 of the frame section 16. It is spaced from the web-like front part 19 and has the upper portion thereof bent laterally outwards at right angles to form a plate piece 27. This plate piece is shaped to conform to one-half of the heel portion of the shoe S and has holes 28 which extend vertically therethrough and accommodate rivets or other attaching devices for securing the heel portion of the shoe in fixed relation with the plate piece 27.
- 45 The frame section 17, like the frame section 16 is in the form of a metal stamping. It fits against and forms the complement of the section 16 and consists of an elongated base part 29, an upstanding web-like front part 30, and an upstanding web-like rear part 31. The base part 29 fits against and is welded to the base part 18 of the frame section 16 and is deflected so that the central portion thereof embodies a longitudinally extending inwardly facing groove 32 and its bottom or lower portion forms a laterally offset seat-forming member 33 with an arcuate shoulder 34 at its front end and an arcuate shoulder 35 at its rear end. The seat-forming member 33 is disposed directly opposite to the seat forming member 22 of the base part 18 of the frame section 16 and is welded to the upper portion of the adjacent face of the runner 12. The shoulder 34 is disposed directly opposite to the shoulder 23 and abuts against the front portion of the upper edge 15 of the runner 12. The shoulder 34 at the rear end of the seat forming member 33 is disposed directly opposite and conforms in shape to the shoulder 24 and rests against the rear portion of the upper edge 15 of the runner 12. The groove 32 is disposed in opposed relation with and opens onto the groove 21 and it like the latter is tapered from the front end thereof to its rear end and is V-shaped in cross-section. The upstanding web-like front part 30 of the frame section 17 fits against and is suitably secured to the web-like front part 19 of the frame section 16 and has its upper portion bent outwardly at right angles to form a plate piece 36. The latter is in the form of a complement of the plate-piece 25 and embodies holes 37 inwardly of the margin or edge thereof. It is shaped conformably to the other side of the sole portion of the shoe and is fixed to such side by way of rivets or like attaching devices extending through the holes 37. The web-like rear part 31 of the frame section 17 is disposed opposite and welded to the rear part 31 of the frame section 16 and has its upper end bent laterally at right angles to form a plate-piece 38. The latter engages and supports the other half of the heel portion of the shoe S and has holes 39 for attaching devices not shown. It is positioned in opposed relation with respect to the plate-piece 27 and is in the form of the latter's complement. The pieces 25 and 36 constitute a sole plate for the frame and the pieces 27 and 38 constitute a heel plate for the frame.
- 50 In order to reinforce and render rigid the frame sections 16 and 17 and to hold the sections against relative vertical displacement a metallic tube 40 is provided. This tube fits within and extends longitudinally of the grooves 21 and 32 in the base parts of the frame sections. It is circular in cross-section and as shown in Figures 6, 7 and 8
- 55 70 75 80 85 90 95 100

is tapered from the front end thereof to the rear end like the grooves 21 and 32. The bottom portion of the tube overlies and engages the upper edge 15 of the runner 12 and forms an abutment 5 whereby the weight which is sustained or supported by the central portion of the frame 13 is transmitted to the central portion of the runner 12. The external diameter of the tube is such that the tube is in firm contact with the central portions of the base parts of the frame sections.

10 The lower portions of the web-like front parts 19 and 30 of the frame sections, that is, the portions between the plate-pieces 25 and 36 and the front ends of the base parts 18 and 29 of said sections are deflected to form a pair of substantially vertically extending channels 41 between the front parts 19 and 30. These channels extend downwardly from the plate pieces 25 and 36 and intersect and communicate with the front 15 ends of the grooves 21 and 32. They are shaped, as shown in Figure 9, so that the front portions thereof are wider than the rear portions, and have tubular struts 42 therein. These struts are 20 formed of metal and are of sufficient cross-section that they conform to or fit snugly or securely within the channels. The lower ends of the struts rest on the front end of the reinforcing tube 40, as shown in Figure 8. The tubes are 25 preferably formed of seamless tubing and serve to prevent lateral bending or deflection of the 30 web-like front parts 19 and 30 of the frame sections and also to prevent relative longitudinal displacement of the frame sections. The central portions of the web-like rear parts 20 and 31 of the 35 frame sections are deflected outwards to form a substantially vertically extending channel 43. This channel extends downwards from the plate-pieces 27 and 38 and intersects and communicates with the rear ends of the grooves 21 and 32 40 of the base parts of the frame sections. It is similar in cross-section to the channels 41 between the web-like front parts of the frame sections and has a tubular reinforcing strut 44 therein. This strut is formed of metal and corresponds 45 in cross-section to the channel 43. The lower end of the strut rests on the rear end of the reinforcing tube 40. The strut 44 serves to prevent lateral bending or deflection of the web-like rear parts 20 and 31 of the frame sections 50 and assists the tubular struts 42 in preventing relative longitudinal displacement of the frame sections.

55 The sole plate forming pieces 25 and 36 which are formed by the upper portion of the web-like front parts 19 and 30 of the frame sections are deflected at the central portions thereof to form a pair of wells 45. These wells extend transversely across the pieces 25 and 36 and preferably the front portions thereof are deeper than the 60 rear portions. A pair of cup-shaped members 46 are associated with and fit within the wells 45 and form bridges whereby the pieces 25 and 36 are cross-connected. These members are in the form of metal stampings and are shaped conformably 65 to the wells. The margins of the members extend upwards, as shown in Figure 10, for strengthening purposes and are flush with the top faces of the plate-pieces 25 and 36, as shown in Figure 2. The wells overlie and communicate 70 with the upper ends of the channels 41 and the upper ends of the tubular struts 42 engage or abut against the central portions of the cup-shaped members 46. As a result of the fact that the upper ends of the struts 42 abut against the 75 central portions of the cup-shaped members a

portion of the weight of the person wearing the skate is transmitted from the members 46 to the reinforcing tube 40, which in turn serves to distribute the load or weight throughout the frame and the runner. The members 46 may, if desired, be welded in the wells or placed loosely therein and held in place by the sole portion of the shoe S. The heel plate-forming pieces 27 and 38 are centrally deflected to form a well 47. This well extends transversely across the two plates 10 and its front portion is deeper than its rear portion, as shown in Figure 4. A cup-shaped member 48 is shaped conformably to, and fits within, the well 47 and serves to bridge or cross-connect the plate pieces 27 and 38. This member 48 is in 15 the form of a metal stamping and has an up-standing margin which serves to reinforce the member as a whole and is flush at its upper edge to the top faces of the pieces 27 and 38. The well 47 overlies and communicates with the upper 20 end of the channel 43 and the upper end of the strut 44 in the channel 43 encases the central portion of the cup-shaped member 48 and transmits load from the latter to the rear end of the tube 40. The cup-shaped members 46 and 48 25 serve in addition to cross-connecting the pieces which form the sole and heel plates of the frame 30 13 to assist the struts 42 and 44 in holding the frame sections 19 and 30 against relative longitudinal displacement.

35 The herein described ice skate, due to the reinforcement that is afforded by the tube 40, the struts 42 and 44, and the cup-shaped members 46 and 48, is able to withstand great shock without breakage and is exceptionally durable. Because 35 of the aforementioned reinforcement it is possible to use comparatively light metal stock in forming the frame sections and hence to make the 40 skate extremely light in weight.

The invention is not to be understood as restricted to the details set forth, since these may be modified within the scope of the appended claims, without departing from the spirit and scope of the invention.

Having thus described the invention what I 45 claim as new and desire to secure by Letters Patent is:

1. As a new article of manufacture, an ice 50 skate comprising a shoe supporting frame composed of a pair of separately formed complementary stamping formed sections fixed together in opposed relation and having pieces at the top thereof forming sole and heel plates for the shoe and also having elongated base parts with the central portions thereof deflected outwards 55 to form longitudinal inwardly facing tapered substantially full length registering grooves, an elongated runner secured to the bottom portions of said base parts of the frame sections beneath the grooves, and an elongated element, fitting 60 snugly in and tapered correspondingly to the grooves and serving to reinforce the frame and also to prevent relative displacement of the frame sections.

2. As a new article of manufacture, an ice 65 skate comprising a shoe supporting frame composed of a pair of separately formed complementary sections fixed together in side by side relation and having pieces at the top thereof forming sole and heel plates for the shoe and also having elongated base parts with longitudinally 70 extending inwardly facing grooves in the central portions thereof and their bottom portions offset laterally in opposite directions, an elongated runner extending lengthwise of the frame and 75

- 5 having the upper portion thereof fitting between the bottom portions of the base parts of the frame sections, and an elongated separately formed element fitting snugly in and extending longitudinally of the grooves and resting on the upper edge of the runner and serving to reinforce the frame and also to prevent relative vertical displacement of the frame sections and to transmit load from said sections to the runner.
- 10 3. As a new article of manufacture, an ice skate comprising an elongated shoe supporting frame having a heel plate at its rear end and consisting of a pair of separately formed complementary sections fixed together in opposed relation and embodying elongated base parts and a pair of abutting web-like parts projecting upwards from the front ends of said base parts and having a sole plate at the top thereof and a substantially vertically extending channel between them, an elongated runner secured to and extending longitudinally of the base parts of the frame sections, and a separately formed strut fitting in the channel and serving to reinforce said web-like parts against bending laterally and also to prevent relative longitudinal displacement of the frame sections.
- 15 4. As a new article of manufacture, an ice skate comprising an elongated shoe supporting frame having a heel plate at its rear end and consisting of a pair of separately formed complementary sections fixed together in opposed relation and embodying elongated base parts with longitudinally extending inwardly facing grooves in the central portions thereof and their bottom portions offset laterally in opposite directions and, in addition embodying a pair of web-like parts projecting upwards from the front ends of said base parts and having a sole plate at the top thereof and a substantially vertical channel between them and leading to and communicating with the front portions of said grooves, an elongated runner extending longitudinally of the frame and having the upper portion thereof fitting between the bottom portions of the base parts of the frame sections, an elongated separately formed reinforcing element fitting snugly in and extending longitudinally of the grooves and resting on the upper edge of the runner and serving to reinforce the frame sections and also to prevent vertical displacement of said sections one relatively to the other, and a separately formed strut fitting in the channel and resting on the front end of the reinforcing element and serving to reinforce said web-like parts against bending laterally and also to prevent relative longitudinal displacement of the frame sections and transmit load to the runner via said reinforcing element.
- 20 5. As a new article of manufacture, an ice skate comprising an elongated shoe supporting frame having a sole plate at its front end and consisting of a pair of separately formed complementary sections fixed together in opposed relation and embodying elongated opposed base parts with longitudinally extending inwardly facing grooves in the central portions thereof and their bottom portions offset laterally in opposite directions, and also embodying opposed web-like parts projecting upwards from the rear ends of the base parts and having a heel plate at the top thereof and a substantially vertical channel between them and communicating with the rear ends of the grooves, an elongated runner extending longitudinally of the frame and having the upper portion thereof fitting between and secured to the bottom portions of the base parts of the frame sections, an elongated reinforcing element fitting snugly in and extending lengthwise of the grooves and resting on the upper edge of the runner and serving to prevent relative vertical displacement of the frame sections, and reinforcing struts fitting in said channels with the lower ends thereof resting on the reinforcing element and serving to prevent relative longitudinal displacement of the frame sections and also to transmit load to the runner via said element.
- 25 6. As a new article of manufacture, an ice skate comprising an elongated shoe supporting frame composed of a pair of complementary sections fixed together in side-by-side relation and embodying elongated base parts with longitudinally extending inwardly facing grooves therein and also embodying opposed web-like parts extending upwards from the base parts and having a channel between the central portions thereof in communication at its lower end with the grooves and their upper ends shaped to form oppositely extending shoe engaging pieces with a well extending trans-
- 30 7. As a new article of manufacture, an ice skate comprising an elongated shoe supporting frame consisting of a pair of separately formed complementary sections fixed together in side-by-side relation and embodying elongated opposed base parts with longitudinally extending inwardly facing grooves in the central portions thereof and their bottom portions offset laterally in opposite directions, and also embodying opposed web-like parts projecting upwards from the front ends of said base parts and having a sole plate at the top thereof and a substantially vertical channel extending between them and leading to and communicating with the front ends of the grooves and opposed web-like parts projecting upwards from the rear ends of the base parts and having a heel plate at the top thereof and a substantially vertical channel extending between them and communicating with the rear ends of the grooves, an elongated runner extending longitudinally of the frame and having the upper portion thereof fitting between and secured to the bottom portions of the base parts of the frame sections, an elongated reinforcing element fitting snugly in and extending lengthwise of the grooves and resting on the upper edge of the runner and serving to prevent relative vertical displacement of the frame sections, and reinforcing struts fitting in said channels with the lower ends thereof resting on the reinforcing element and serving to prevent relative longitudinal displacement of the frame sections and also to transmit load to the runner via said element.
- 35 8. As a new article of manufacture, an ice skate comprising an elongated supporting frame composed of a pair of complementary sections fixed together in side-by-side relation and embodying elongated base parts with longitudinally extending inwardly facing grooves therein and also embodying opposed web-like parts extending upwards from the base parts and having a channel between the central portions thereof in communication at its lower end with the grooves and their upper ends shaped to form oppositely extending shoe engaging pieces with a well extending trans-
- 40 75 75

versely thereacross and in communication with the upper end of the channel, an elongated runner fitting between and secured to the bottom portions of the base parts of the frame sections and having the top edge thereof facing the grooves, an elongated reinforcing element fitting snugly in and resting on the top edge of the runner and serving to prevent relative vertical displacement of the frame sections, a reinforcing

strut fitting in the channel with the lower end thereof resting on the reinforcing element, and a reinforcing member fitting in and extending transversely across the well and arranged so that it rests on the upper end of the strut and serves to cross-connect the shoe engaging pieces and also to transmit the load from the shoe to the runner via the strut and said reinforcing element.

CHARLES I. JOHNSON.
